UNITED STATES PATENT OFFICE

PAUL FALZ, OF ST. PAUL, MINNESOTA, ASSIGNOR OF ONE-HALF TO MINNIE HELWIG, OF ST. PAUL, MINNESOTA

OIL BURNER

Application filed June 29, 1931. Serial No. 547,535.

It is the object of this invention to provide a novel oil burner of the type wherein a circular spray of oil is formed by a rotary, motor-driven head.

More particularly, it is my object to provide means for securing improved distribution of oil within the rotary head and for securing better control of the air supply beneath the spray whereby uniformity in the height of the flame around the circumference of the fire ring is secured.

The invention also includes certain other novel features of construction which will be more fully pointed out in the following specification and claims.

The device will be best understood by reference to the accompanying drawings in which:

Figure 1 is a side elevation of my improved oil burner, separate from the fire ring;

Fig. 2 is a plan view of the same with the cover plate for the distributor head removed;

Fig. 3 is a horizontal section taken on the line 3—3 of Fig. 1;

Fig. 4 is a central, vertical section through the burner, fire ring and adjacent portions of the furnace;

Fig. 5 is a horizontal section taken on the line 5—5 of Fig. 4; and

Fig. 6 is a fragmentary section taken on the line 6—6 of Fig. 4.

My improved burner has supporting legs 7, preferably provided with feet 8 of rubber or other more or less resilient material adapted to reduce the transmittal of vibrations from the motor to its supporting surface. These legs have screw threaded upper portions 7a and nuts 7b threaded thereon to permit adjustment of the effective length of the legs and at their upper ends the legs are rigidly fastened to a frame ring 9. Secured by screws 10 to the inner periphery of the ring 9 is a main body casting 11 having a central, vertical opening, the lower end of which is threaded to receive a threaded nipple 12 (Figs. 3 and 4) integral with a supporting bracket 13 for an electric motor 14. This motor is attached by screws 50 15 to the bracket 13 and has a vertical shaft

16 extending upward in an axial opening in the body casting 11.

Rigidly secured to the upper end of the shaft 16 is a cover plate 17. This plate engages a cross pin 18 extending through a perforation in the shaft 16 and has a cap screw 19 engaging its upper surface and threaded in an axial, tapped bore in the shaft 16. The plate 17 is circular and its outer periphery is secured by a series of small cap screws engaging in tapped holes 20 (Fig. 2) formed in a rotary head 21. Within the head 21 a cup 22 is formed to receive the oil and projecting from the outer, lower periphery of the head is a series of substantially triangular fan blades 23.

Four outlet openings 24 extend horizontally through the periphery of the head 21, said openings being equally spaced around the upper periphery of the cup 22 to direct the oil against a fire ring 25 (Fig. 4). At its inner, lower periphery the head 21 is formed with an annular lip 26. Rigidly fastened to the body casting, above the lip 26, is an oil distributor plate 27. As shown in Figs. 2 and 4, four openings 28 are equally spaced around the periphery of the plate 27 to supply the oil within the cup 22. The openings 28 communicate with vertical passages 29 extending downward to an annular passage 30 which, in turn, communicates with drilled passages 31 and 32 in the body casting 11. Oil is supplied to the lower end of the passage 32 by a pipe 33 having a suitable connection therewith, as shown in Fig. 4.

Air is admitted to an annular chamber 34 through a series of equally spaced peripheral openings 35 in an annular flange 36 integral with the ring 9. An air control ring 37 is revoluble on the outer surface of the flange 36 and has openings 38 adapted to be placed in registry with the openings 35. By turning the ring 37, the openings 35 and 38 may be partially closed, as will be readily understood. An extension 39 of the annular flange 36 projects upward to afford an abutment for refractory material 40 which is supported on a plate 41 engaging in an annular groove at the upper periphery of the flange 36. At its outer edge the plate 41 is supported on a

fire box 42 having a water jacket 43 of common type.

To install my improved burner, the effective length of the legs 7 is adjusted to bring 5 the head 21 at the proper height within the fire box and then the plate 41 is inserted and the refractory material 40 and fire ring 25, positioned as indicated in Fig. 4. In operation the motor 14 rotates the shaft 16 and 10 head 21 at the desired high speed and oil is admitted through the pipe 33 and passages 32, 31, 30 and 29 so that it is delivered in four streams to the distributor plate 27. This plate delivers the fuel to the central 15 portion of the cup 22 and, by centrifugal force, the fuel is thrown up the sides of said cup and out through the openings 24, being delivered in a fine spray outward against the fire ring 25 where it burns. The desired 20 mixture with air takes place as the spray of oil is thrown outward, the air entering through the openings 38 in the ring 37 and passing through the openings 35 to the chamber 34 which delivers it to the lower and 25 inner periphery of the fan blades 23. The proper supply of air is secured by rotary adjustment of the ring 37.

I have found that my improved burner is highly efficient and secures an unusually 30 uniform height of circular flame by reason of the equal distribution of the oil within the cup 22 and accurate control of the air supply.

Having described my invention, what I 35 claim as new and desire to protect by Letters Patent is:

1. An oil burner having in combination supporting frame, a motor mounted centrally on said frame and having a vertical drive 40 shaft, a rotary head secured to the upper end of said shaft, an oil cup concentric with said shaft on said head and having a central, annular opening therein, a main body casting supported on said frame and formed with a 45 portion projecting upward in said opening and a distributing plate secured to the upper extremity of said body portion for delivering oil to said cup, said casting being drilled to provide a plurality of oil supplies 50 equally spaced around said distributor plate, and said plate overlapping the inner periphery of said cup to close said opening and having an outlet opening communicating with each 55 of said supplies.

2. An oil burner having in combination a motor having a vertical drive shaft, a rotary head, a circular plate secured to the upper end of said shaft, means removably securing 60 the outer periphery of said head to the outer periphery of said plate, an oil cup formed in said head beneath said plate and having a central opening adjacent to said shaft, a frame member extending upwardly in said 65 opening and formed with a plurality of oil

supplies equally spaced around the central opening in said cup and a distributor plate secured to the upper end of said frame member and overlapping the inner periphery of said cup to close said opening.

3. An oil burner comprising, a supporting frame, a motor adjustable vertically on said frame and having a vertical drive shaft extending upward, a rotary head fixed on the upper end of said shaft, an oil cup formed in said head and having a central, bottom opening around said shaft, a fixed projection on said frame extending upward in said opening and formed with a plurality of passages to deliver oil to said cup and a distributing plate fixed on the upper end of said projection and overlapping the inner periphery of said cup to distribute oil from said passages within said cup.

In testimony whereof, I have hereunto signed my name to this specification.

PAUL FALZ.
